UNITED STATES PATENT OFFICE.

MORTIMER C. FOSTER, OF NEW YORK, N. Y., ASSIGNOR TO AUGUST GOLDSMITH, MORTIMER C. FOSTER, NATHAN B. STERN, AND ARTHUR SIMONS, DOING BUSINESS AS GOLDSMITH, STERN & CO., OF NEW YORK, N. Y.

DESIGN FOR A LORGNETTE.

44,759.

Specification for Design.

Patented Oct. 21, 1913.

Application filed August 9, 1913. Serial No. 783,964. Term of patent 3½ years.

To all whom it may concern:

Be it known that I, MORTIMER C. FOSTER, a citizen of the United States, and a resident of the city of New York, county of New York, and State of New York, and whose post-office address is 815 West End avenue, in said city, have invented a new, original, and ornamental Design for Lorgnettes, of which the following is a specification.

Reference is to be had to the accompanying drawing, in which—

nettes; and Fig. 2 is a side elevation of the same.

I claim:

The ornamental design for a lorgnette as shown.

Signed at the city of New York, county of New York, and State of New York, this 8th day of August, 1913.

MORTIMER C. FOSTER.
